UNITED STATES PATENT OFFICE.

ALBERT SCHANFLER, OF GREENSBURG, INDIANA, ASSIGNOR OF ONE-HALF TO EDMUND H. MOHR, OF GREENSBURG, INDIANA.

CLAMP FOR STOVEPIPES.

972,652.

Specification of Letters Patent. Patented Oct. 11, 1910.

Application filed March 12, 1909. Serial No. 482,968.

To all whom it may concern:

Be it known that I, ALBERT SCHANFLER, a citizen of the United States, residing at Greensburg, in the county of Decatur and 5 State of Indiana, have invented new and useful Improvements in Clamps for Stovepipes, of which the following is a specification.

This invention relates to clamps for stove 10 pipes, and the like, the object of the invention being to provide a simple, economical and effective clamp having a two-fold function, first, to clamp a flue cap or collar in place in front of a flue hole and secondly, to 15 clamp the inner section of a stove pipe in place relatively to said flue hole and collar.

With the above and other objects in view, the nature of which will more fully appear as the description proceeds, the invention 20 consists in the novel construction, combination and arrangement of parts as herein fully described, illustrated and claimed.

In the accompanying drawings:—Figure 1 is a sectional view of the device of this 25 invention. Fig. 2 is a perspective view thereof looking toward the inner side of the device.

1 designates a flue cap or collar of the usual concavo-disk form adapted to be centrally cut away to form a center opening 2 30 of any size, commensurate with the external diameter of the stove pipe indicated at 3. Secured movably to the rear side of the part 1 is a pair of spring clamps 4 and 5 35 each of which is preferably composed of spring wire bent into wicket-form or U-shape as clearly shown in Figs. 1 and 2, where they cross each other being reversely offset as shown at 6 so as to pass by each 40 other in substantially the same plane and interlock at their points of crossing, the spring clamps being rendered self-centering and mutually bracing in this manner. The terminals of the spring clamp are bent 45 inward radially as shown at 7 and inserted into or through the clips or eyes 8 which act

as guides for the inbent ends 7 and serve to direct the movements thereof in radial paths toward and away from the central opening 2. These clips may be formed of sheet 50 metal of any suitable gage.

When the device as a whole is inserted through a flue hole indicated at 9 in Fig. 1, the spring clamps 4 and 5 are compressed by the sides of the flue hole, the result being 55 that the inner ends of the terminals 7 of the clamps are pressed inward toward each other and toward the stove pipe section 3 which is inserted through the central opening 2. The spring clamps 4 and 5 friction- 60 ally engage and bind within the flue hole and the extremities of the terminals 7 are caused to impinge against the stove pipe at diametrically opposite points thereby obtaining a firm hold or grip on the stove pipe 65 which will prevent the accidental escape thereof. The device is economical in manufacture and will be found practical in use. The cover or cap 1 is usually put on the market without the central opening 2 so that 70 said opening may be cut subsequently to suit the particular size of stove pipe employed in connection therewith.

I claim:—

The combination with a flue collar, of a 75 circular series of guides on the inner side of the collar and ranged around the central opening thereof, and a plurality of wicket shaped spring clamps crossing each other at an angle and having inbent end portions 80 fitted to slide in said guides, and so arranged that when the device is forced into the flue opening, the extremities of the inbent end portions are forced inwardly to engage the outer surface of the stove pipe and 85 lock the same in position.

In testimony whereof I affix my signature in presence of two witnesses.

ALBERT SCHANFLER.
